CLAIM

The ornamental design for a baby seat with bag, as shown and described.

DESCRIPTION

FIG. 1 is a front, left, and bottom perspective view of a baby seat with bag, showing my design.

FIG. 2 is a rear, right, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a zipper head.

FIG. 10 is a partial enlarged view of an area labeled 10 in FIG. 1 comprising a zipper.

FIG. 11 is a perspective view of the baby seat with bag of FIG. 2 wherein the baby seat is opened from behind the bag; and,

FIG. 12 is a partial enlarged view of an area labeled 12 in FIG. 11 comprising a zipper.

The broken lines shown in the drawings are included for the purpose of illustrating portions of the baby seat with bag that form no part of the claimed design.

1 Claim, 12 Drawing Sheets
